US00D851297S

(12) **United States Design Patent** (10) Patent No.: **US D851,297 S**
 Dennis et al. (45) Date of Patent: ** Jun. 11, 2019

(54) **LIGHTING DEVICE**(71) Applicant: **Lightforce Australia Pty Ltd.**,
Hindmarsh (AU)(72) Inventors: **Raymond L. Dennis**, Adelaide (AU);
Robert T. Dall, Adelaide (AU)(73) Assignee: **Lightforce Australia Pty Ltd.**,
Hindmarsh (AU)(**) Term: **15 Years**(21) Appl. No.: **29/617,470**(22) Filed: **Sep. 14, 2017**(51) LOC (11) Cl. **26-06**

(52) U.S. Cl.

USPC ..... **D26/28**; D26/63(58) **Field of Classification Search**

USPC D26/24, 28, 63, 66, 67, 74, 118;

Primary Examiner — Garth Rademaker*Assistant Examiner* — Katelin G Kloberg(74) *Attorney, Agent, or Firm* — Wood Herron & Evans LLP(57) **CLAIM**

The ornamental design for a lighting device, as shown and described.

DESCRIPTION

FIG. 1 is a front isometric view of the lighting device;

FIG. 2 is a rear isometric view;

FIG. 3 is a front elevational view;

FIG. 4 is a rear elevational view;

FIG. 5 is a left side elevational view;

FIG. 6 is a right side elevation view;

FIG. 7 is a top plan view; and,

FIG. 8 is a bottom plan view.

The broken lines shown in the drawings depict portions of the article and form no part of the claimed design.
